Alpheus Walker

United States Patent Office.

ALPHEUS WALKER, OF WORCESTER, MASSACHUSETTS.

Letters Patent No. 101,396, dated March 29, 1870.

IMPROVEMENT IN TROWELS.

The Schedule referred to in these Letters Patent and making part of the same.

To all whom it may concern:

Be it known that I, ALPHEUS WALKER, of the city and county of Worcester, and Commonwealth of Massachusetts, have invented certain new and useful Improvements in Trowels; and I do hereby declare that the following is a full, clear, and exact description of the same, reference being had to the accompanying drawings forming a part of this specification, in which—

Figure 1 represents a perspective view of my improved trowel, and

Figure 2 represents a central longitudinal section of the same.

To enable those skilled in the art to which my invention belongs to make and use the same, I will proceed to describe it more in detail.

The nature of my invention consists in an improved trowel, the neck and ferrule of which are constructed and combined together in the peculiar manner shown in the drawings, and hereinafter explained, whereby the objectionable wearing of the operator's thumb and forefinger, incident to all trowels as heretofore constructed, is entirely obviated.

In the drawings—

The part marked A is the blade of the trowel;

B, the shank thereof;

C, the wooden handle;

D, the ferrule; and

E, the butt-piece.

The neck b, or upright portion of the shank B, is made in cylindrical shape, and a small shoulder, c, is formed thereon, just below the curved part a, to receive the end of the ferrule D, which is cast with its forward end, d, curved over and diminished, so as to cover the curved part a, and to fit closely around the shank B, and against the shoulder c, as shown in the drawings.

The wooden part of the handle C is turned to fit the rear end of the ferrule D and the butt-piece E, and is provided with an opening through its center for the shank B.

The butt-piece E is made about three-eighths of an inch in thickness, and has a flange, e, around its edge, which holds the rear end of the wooden part C. An opening is formed through its center to receive the end of the shank B, upon which it is screwed or riveted.

The neck b, shoulder c, and curved part a of the shank are all formed by swaging them in suitable dies, so that, when making a number of trowels, all the parts will be of uniform size.

In putting the parts together, the ferrule D is passed over the curve a of the shank, so that its end d rests against the shoulder c. The wooden part C is then placed on the shank B, after which the butt-piece E is screwed onto the end f of the shank; or it may be arranged thereon, and the end f riveted down, if preferred, in which case the butt-end E should be slightly countersunk at its outer side. The end d of the ferrule is then finished off flush with the neck b, thus leaving a smooth and uniform surface from the blade A to the handle C, whereby there is no liability of mortar gathering and sticking upon the neck at the junction of the ferrule therewith. Then, again, there are no projections or uneven surfaces at the junction of the ferrule with the neck to wear and chafe the thumb and forefinger of the operator when the trowel is in use. My improved trowel is, besides, very strong, and not liable to break in use.

Having described my improved trowel,

What I claim therem as new and of my invention, and desire to secure by Letters Patent as an improved article of manufacture, is—

A trowel, the neck and ferrule of which are constructed and combined together in the peculiar manner herein described, so that the end of the ferrule which fits against the shoulder on the neck shall be flush with the neck, for the purposes set forth.

ALPHEUS WALKER.
